(57) **CLAIM**

The ornamental design for “icon of a multiple CD changer for a display screen”, as shown and described.

DESCRIPTION

A portion of the disclosure of this document contains material which is subject to copyright protection. The copyright owner has no objection to the facsimile reproduction by anyone of the patent document or patent disclosure, as it appears in the Patent and Trademark Office patent file or records, but otherwise reserves all copyright rights whatsoever.

The single FIGURE is a front view of an icon of a multiple CD changer for a display screen showing our new design.
